PINKING MECHANISM

William N. Sobel and Herbert V. Jacobs,
Philadelphia, Pa.

Application February 1, 1939, Serial No. 253,984

8 Claims. (Cl. 112—125)

The invention relates to pinking mechanism and involves improved means for rendering such mechanism operative and inoperative at will and positioning the movable cutter blade into and out of cooperative relation with the stationary cutter blade without interrupting or interfering with the usual stitching operation of the sewing machine with which the improvement is used. The invention has to do particularly with pinking mechanism of the type wherein a stationary cutter or ledger blade is positioned adjacent the stitching mechanism of the sewing machine, and the movable cutter blade is reciprocated relatively to the stationary cutter blade by means of a pitman structure which receives its reciprocating motion from the driving mechanism of the sewing machine.

In some of the pinking devices heretofore used in combination with sewing machines, no means have been provided for discontinuing the pinking operation at the will of the operator. It is frequently desirable or necessary in a combined stitching and pinking operation to discontinue the pinking operation during certain portions of the stitching operation. In structures where no means are provided for throwing the pinking device into and out of operation at will, it is necessary to remove the work from the combined stitching and pinking machine so that the stitching operation alone can be carried out on an independent machine not equipped with a pinking device. The use of separate machines in this manner is troublesome and expensive.

In attempting to overcome the difficulties inherent in machines of the type referred to, manual means have heretofore been provided for operatively disconnecting the pinking device from the driving mechanism of the sewing machine. Such means have not been satisfactory in operation, and so far as we are aware no means has been provided heretofore for operatively connecting and disconnecting the pinking device from the driving mechanism of the sewing machine where a pitman structure or the like is employed for positively transmitting motion in both directions from the driving mechanism of the sewing machine to the movable cutter of the pinking device.

The principal object of the present improvement is the provision of a simple coupling device in the motion transmitting means between sewing machine driving mechanism and a pinking attachment whereby the movable cutter blade of the pinking device may be thrown into and

out of operation at will, without interfering with the stitching operation performed by the sewing machine. Other objects and advantages of the improvement will be apparent from the following description, taken with the accompanying drawings wherein:

Fig. 1 is a front elevational view of a sewing machine with our improved pinking device attached thereto, the movable cutter blade and associated parts being shown in their uppermost position when in use and our improved coupling member being shown in operative condition;

Fig. 2 is an end elevational view, partly cut away, showing our improved coupling device with the parts thereof in position to transmit motion from the driving mechanism of the sewing machine to the movable cutter blade of the pinking device;

Fig. 3 is a similar view showing the coupling device with the parts disconnected; and

Fig. 4 is a rear elevational view of the pinking device with the movable cutter blade and associated parts in their lowermost position of use.

The invention is illustrated in the drawings in combination with a sewing machine provided with the usual bed plate or work support 10, a standard 11 projecting upwardly from one end thereof and having an overhanging arm 12 extending from its upper end over the bed plate, 30 and provided with the usual head 13 on its outer end. Power from an electric motor or other suitable source is applied to the sewing machine by means of a belt passing over a driving pulley 14 secured on the outer end of the main drive shaft 15. Suitable motion transmitting means on the opposite end of the drive shaft 15 serves to reciprocate the needle bar 16 within the head 13, together with the needle 17 carried thereby. The work is held in place on the work support 10 by 40 a presser foot 18 carried by the lower end of a manually operable presser bar 19 supported in the head 13. The stitching operation is performed by the reciprocating needle 17, in cooperation with any known form of feed mechanism and loop-forming mechanism positioned beneath the bed plate 10.

As illustrated in the drawings, our improvement is incorporated in a pinking device having a stationary cutter or ledger blade 20 positioned 50 adjacent the stitch-forming mechanism, and a reciprocating cutter 21 receiving its motion from the drive shaft 15 of the sewing machine. The pinking attachment is mounted upon a base 22 which is adjustably secured to the bed plate 10 by suitable means such as a set screw 23. The

ledger blade 20 is preferably secured to the lower side of the base 22 in such a manner as to project outwardly from one end of the base into a position adjacent the stitch-forming mechanism, and is provided with a V-shaped opening to form shearing edges for cooperation with the shearing edges of cutter 21 as is well understood in the art. Guide elements 24 projecting upwardly from the ledger blade serve to guide the movable cutter 21 in its reciprocating cutting movements.

The movable cutter 21 is likewise V-shaped in cross section, and is removably secured to the lower end of a cutter arm 25 by means of a set screw 26. At its upper end the cutter arm 25 is pivoted on a pin 27 in the outer end of a cutter supporting arm 28, the opposite end of which is pivoted at 29 to the base 22. The movable cutter 21 is resiliently urged into cooperative engagement with the cutting edges on the ledger blade 20 by an adjustable spring device comprising a link member 30, a bell crank 31 pivoted on a screw 32 extending transversely through the cutter supporting arm 28, and a coiled spring 33 having one end secured to the bell crank 31 and its other end secured to the inner end of a pin 34 extending outwardly through one end of the cutter supporting arm 28 and threaded on its outer end to receive a manually operable adjusting nut 35.

In pinking mechanism of the general type to which our improvement is applied, it is essential that the movable cutter 21 be reciprocated in timed relation with the stitching mechanism of the sewing machine and the feed mechanism employed therewith. In the present improvement the reciprocating motion of the movable cutter 21 is obtained from the drive shaft 15 by means of reduction gearing, of which one element 36 is secured to the drive shaft 15 and the other 37 is secured to the end of a jack shaft 38 supported in suitable bearings in a bracket 39 suspended from the overhanging arm 12. The gear reduction is ordinarily a two-to-one ratio, thus providing one reciprocation of the movable cutter 21 for every two reciprocations of the needle bar 16.

The end of the jack shaft opposite gear 37 is provided with a head 40 having a wrist pin 41 secured therein. A ball head 42 on the outer end of the wrist pin 41 engages within a ball socket in the head 43 of a pitman structure which transmits motion to the cutter supporting arm 28. A pitman rod 44 extends downwardly from the pitman head into a socket 45 formed in a coupling member 46. A ball socket on the lower end of coupling 46 receives a ball head 47 on the outer end of a pin 48 threaded into a lug 49 which projects upwardly from the cutter supporting arm 28.

The pitman rod 44 is freely slidable in the socket 45, and the means which we have provided for releasably connecting the rod 44 and the coupling member 46 together comprises a yoke 50 the side arms 51 of which are pivoted to the coupling member 46 by screws 52. The loop portion 53 of the yoke may be cut away as shown at 54 to partly encircle the pitman rod 44 and engage within a notch 55 arranged transversely therein. The free end of the yoke 50 is urged toward the pitman rod 44 by means of a coiled spring 56 having one end in contact with the yoke and its opposite end in contact with a curved abutment 57 projecting outwardly from the coupling member 46. As will be apparent from the drawings, when the loop portion of the

yoke is in engagement with the notch 55, the pitman rod 44 and the coupling member 46 will be connected together so that the reciprocating motion of the pitman rod will be transmitted through the coupling member 46, the cutter supporting arm 28 and the cutter arm 25 to the movable cutter 21. When, however, the loop portion of the yoke is out of engagement with the notch 55, the pitman rod is free to reciprocate in the socket 45 without moving the coupling member 46 therewith.

In order to disengage the yoke from the notch 55, we have provided a manually operated lever 57 straddling the coupling member 46 and pivoted thereon by screws 58. The free end of the lever 57 is arranged to be moved upwardly to disconnect the coupling member from the pitman rod, and to be moved downwardly for the purpose of freeing the yoke to connect the coupling member with the pitman rod. As will be clear from Figs. 2 and 3 of the drawings the arms of the yoke are notched as shown at 59 for engagement with a nose 60 on the lever 57 to retain the yoke in its inoperative position when the free end of the lever is in its raised position. It will be apparent that the direction of movement of the hand lever 57 to disconnect the coupling member from the pitman rod is in the direction of movement of the movable cutter when it is moved out of pinking operation. Movement of the lever downwardly serves to release the yoke for engagement with the notch 55 and thereby operatively connect the coupling member to the pitman rod. This downward movement of the hand lever is in the same direction in which the movable cutter moves from inoperative to operative position. This arrangement of the lever has been found advantageous to the operator of the machine inasmuch as the direction of movement of the lever is always indicative of the direction in which it is desired to move the movable cutter both into and out of operating positions.

While the structure heretofore described is one in which the cutter supporting arm 28 is positively reciprocated in both directions when the coupling member 46 is operatively connected to the pitman rod 44, additional means have been provided in the form of a spiral spring 61 for raising the movable cutter 21 out of cooperative engagement with the stationary cutter 20 when the coupling member is disconnected from the pitman rod. The lower end of the spring 61 is supported upon the base 22 and its upper end engages with the free end of the cutter supporting arm 28. The swinging movement of the cutter supporting arm 28 upwardly is limited by a stop member in the form of a post 62 projecting upwardly from the base 22 and having its upper end 63 angularly bent into a position to contact with the cutter supporting arm as it is urged upwardly by the hand lever 57 or by the spring 61.

The improvement disclosed herein provides a structure in which the pinking operation may be discontinued at any time by a slight upward pressure upon the free end of the hand lever 57. The cam formation of the inner end of this hand lever is such as to move the yoke 50 upon the pivot screws 52 and thus disengages the loop 53 from the notch 55. The nose 60 on the hand lever retains the yoke in its unlatched position as shown in Fig. 3, so that the pitman rod 44 is free to reciprocate in the socket 45 of the coupling member. When the yoke has thus been disengaged from the notch 55, the expanding action of spring 61 raises the cutter supporting arm 28

into engagement with the stop 63, and the movable cutter 21 is thus raised out of engagement with the stationary cutter 20. With the parts in this position, the stitching operation alone may be continued. When it is again desired to throw the pinking device into operation, this may be done by a slight downward pressure upon hand lever 57 to move it from the position shown in Fig. 3 to the position shown in Fig. 2. When the hand lever is moved downwardly in this manner, the yoke 50 is free to move under the influence of spring 56 so that the loop portion 53 may engage with notch 55 upon the next movement of the pitman rod to bring the notch into proper position. This position of the parts is illustrated in Fig. 2 of the drawings, and, as will be apparent therefrom, the reciprocating movements of the pitman rod are transmitted to the movable cutter 21 through the coupling member 46 and the supporting arm 28. The pinking operation will then be resumed and continue simultaneously with the stitching operation until such time as it may again be desired to discontinue it. The improved coupling therefore provides means whereby the pinking device may be thrown into and out of operation at will, without interfering with the continued operation of the stitching mechanism.

While certain structural forms of the invention have been disclosed herein, together with the preferred arrangement of the various parts with respect to each other, it is to be understood that the invention is not intended to be limited to the precise structure and arrangement of parts as shown and described. The above description and the accompanying drawings are therefore to be regarded as illustrative only of the form and arrangement of the various elements of the improvement, and it is to be understood that the invention is susceptible of other forms and arrangements so long as they come within the scope of the appended claims.

What we desire to claim as our invention is:

1. In combination with a sewing machine having stitching means and driving mechanism therefor, a pinking device including a stationary cutter associated with said stitching means, and a movable cutter cooperating with said stationary cutter, means for reciprocating said movable cutter comprising a pitman having one end connected to said driving mechanism for reciprocation thereby and its opposite end connected to said movable cutter, means for automatically urging said movable cutter in a given direction out of cooperating engagement with said stationary cutter, and manually actuated means movable in said direction for disconnecting said pitman from said movable cutter and urging said movable cutter out of cooperative engagement with said stationary cutter.

2. In combination with a sewing machine having stitching means and driving mechanism therefor, a pinking device including a stationary cutter associated with said stitching means, and a movable cutter cooperating with said stationary cutter, a pitman having one end connected to said driving mechanism for reciprocation thereby, a coupling on the opposite end of said pitman for connecting the same with said movable cutter and disconnecting the same therefrom, and manually operated means movable in a direction to disconnect said coupling and urge said movable cutter out of cooperative engagement with said stationary cutter.

3. The combination with a sewing machine

having stitching and driving mechanism, of a pinking device comprising a stationary cutter associated with said stitching mechanism, a movable cutter cooperating with said stationary cutter and arranged for movement out of cooperative engagement therewith, a pitman interconnecting said driving mechanism and said movable cutter for reciprocating the latter, a manually actuated coupling in said pitman for operatively connecting and disconnecting the same at will, said coupling including a socket member pivotally connected to said movable cutter and having a socket therein for slidably receiving the pitman rod, releasable means urged in one direction for connecting said pitman rod to said socket member, and manually actuated means for urging said releasable means in the opposite direction.

4. A pinking device operated by the driving mechanism of a sewing machine, comprising a stationary cutter, a movable cutter cooperating therewith, a pitman rod having its head end connected to said driving mechanism for reciprocation thereby and having a transversely arranged notch therein, a coupling member connected to said movable cutter by a ball and socket joint and having a socket therein to receive the opposite end of said rod with a sliding fit, a latch mounted on said coupling member for movement into and out of engagement with said notch, spring means for urging said latch into a position to engage with said notch, and manual means for disengaging said latch from said notch.

5. A pinking device operated by the driving mechanism of a sewing machine, comprising a stationary cutter, a movable cutter cooperating therewith, a pitman rod having its head end connected to said driving mechanism for reciprocation thereby and having a transversely arranged notch therein, a coupling member operatively connected to said movable cutter by a ball and socket joint and having a socket therein to receive the opposite end of said rod with a sliding fit, a latch pivoted on said coupling member for movement into and out of engagement with said notch, a spring abutment on said coupling member, a spring between said abutment and said latch for urging said latch into engagement with said notch, and a handle pivoted on said coupling member for movement in one direction to release said latch from said notch and for movement in the opposite direction to free said latch for actuation by said spring.

6. A pinking device comprising a stationary cutter, a movable cutter supported for cooperation therewith and for movement out of engagement therewith, resilient means for urging said movable cutter out of engagement with said stationary cutter, driving mechanism, a pitman rod having its head end connected to said driving mechanism for reciprocation thereby, a coupling member connected to said movable cutter for movement therewith and having a socket therein to receive the opposite end of said rod with a sliding fit, cooperating means on said coupling member and said rod for releasably connecting said coupling member and said rod together, and manual means on said coupling member for rendering said cooperating means ineffective upon movement of said manual means in a direction to urge said movable cutter out of engagement with said stationary cutter.

7. A pinking device comprising a stationary cutter, a movable cutter, driving mechanism, a coupling member connected to said movable cutter by a universal joint and having a socket there-

in, a pitman rod having its head end connected to said driving mechanism for reciprocation thereby and having its opposite end slidably received in said socket, cooperating means on said coupling member and said rod for releasably connecting said rod and said coupling member together, manual means on said coupling member and movable in one direction for actuating said cooperating means to disconnect said rod and said coupling member whereby said rod may reciprocate in said socket, and automatic means for actuating said cooperating means to connect said rod and said coupling member upon movement of said manual means in the opposite direction.

8. In a pinking device for a sewing machine, a movable cutter, a support therefor, a pitman rod having a notch arranged transversely therein and a head on one end for attachment to the

driving mechanism of the sewing machine, a coupling member for attachment to said support and having a socket therein to receive the opposite end of said rod, a yoke having the free end of its arms pivoted to said coupling member for movement of the loop portion thereof into and out of engagement with said notch, an abutment projecting outwardly from said coupling member, a spring mounted between said abutment and said yoke, and a manually operated lever pivoted on said coupling member for movement in one direction to urge said yoke out of engagement with said notch and for movement in the opposite direction to free said yoke for movement by said spring into a position to engage with said notch.

WILLIAM N. SOBEL.
HERBERT V. JACOBS.
